(57) **CLAIM**

The ornamental design for a retainer clip, as shown and described.

DESCRIPTION

FIG. 1 is a top, front and left side isometric view of a first embodiment of a retainer clip in accordance with the new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a rear elevation view thereof; and

FIG. 7 is a front elevation view thereof;

FIG. 8 is a top, front and left side isometric view of a second embodiment of a retainer clip in accordance with the new design;

FIG. 9 is a top plan view thereof;

FIG. 10 is a bottom plan view thereof;

FIG. 11 is a left side elevation view thereof;

FIG. 12 is a right side elevation view thereof;

FIG. 13 is a rear elevation view thereof; and

FIG. 14 is a front elevation view thereof;

FIG. 15 is a top, front and left side isometric view of a third embodiment of a retainer clip in accordance with the new design, in which the appearance of any portion of the article between the break lines forms no part of the claimed design;

FIG. 16 is a top plan view thereof;

FIG. 17 is a bottom plan view thereof;

FIG. 18 is a left side elevation view thereof;

FIG. 19 is a right side elevation view thereof;

FIG. 20 is a rear elevation view thereof; and

FIG. 21 is a front elevation view thereof;

FIG. 22 is a top, front and left side isometric view of a fourth embodiment of a retainer clip in accordance with the new design, in which the appearance of any portion of the article between the break lines forms no part of the claimed design;

FIG. 23 is a top plan view thereof;

FIG. 24 is a bottom plan view thereof;

FIG. 25 is a left side elevation view thereof;

FIG. 26 is a right side elevation view thereof;

FIG. 27 is a rear elevation view thereof; and,

FIG. 28 is a front elevation view thereof.

1 Claim, 20 Drawing Sheets
